Patented Sept. 8, 1925.

UNITED STATES PATENT OFFICE.

JOHN M. ABRAMS, OF BROOKLYN, NEW YORK

ELECTRIC-LIGHT FIXTURE.

Application filed June 3, 1924. Serial No. 717,492.

To all whom it may concern:

Be it known that I, JOHN M. ABRAMS, a citizen of the United States, and a resident of Brooklyn, in the county of Kings and 5 State of New York, have invented certain new and useful Improvements in Electric-Light Fixtures, of which the following is a specification.

The invention relates to an improved fixture for electric lamps, more especially of the miniature type, and designed for use generally in connection with dry cells. It has for its object to provide a fixture of this type which may be readily and quickly 10 attached to and be carried by a dry cell of the usual well-known type, and which fixture shall be simple in construction and inexpensive in manufacture. The novel fixture, moreover, is of such dimensions and 15 construction that, when not in use, it may be conveniently stored or pocketed and, also, may be economically shipped—affording a satisfactory mail order article. A further 20 object of the invention is to eliminate all switching and like devices in connection with a fixture of this type, the electric circuit for operating the lamp to be carried thereby being established directly by one of 25 the binding posts of the cell; or, preferably, 30 by the nut working thereon.

The nature of the invention, however, will best be understood when described in connection with the accompanying drawings, in which—

35 Fig. 1 is a side elevation of a portion of a dry cell with the novel fixture attached, with circuit to the lamp carried thereby shown open.

Fig. 2 is a vertical section thru the fixture, 40 and shows also the circuit to the lamp closed.

Fig. 3 is a plan of the cell with fixture attached; and Fig. 4 is an end view of the latter.

Figs. 5 and 6 are respectively a side and 45 rear elevation of the fixture equipped with reflector.

Referring to the drawings, 10 designates a dry cell of ordinary construction and provided with the usual threaded terminals as 50 the binding posts 11 and 12 upon which are mounted nuts 13 and 14 respectively, ordinarily employed to secure conductors to the terminals.

In the present instance, however, one of 55 these terminals, as the terminal 12, is designed to carry the novel fixture 15 as by se-

curing thereto the flattened bent-over and perforated end 16 thereof in screwing down the nut 14 thereon. The bracket proper extends substantially at right angles from the flattened end 16 and then outwardly parallel thereto so as to be displaced from the upper surface of the cell 10; and at its outer end is curved sufficiently to provide a cylindrical receptacle or socket 17. This socket 60 is provided with pressed threads to receive the base of a lamp 18, as is well understood, and is to be so positioned relatively to the terminal 11 as to be substantially coaxial therewith. The lower end of the socket 17, 70 however, is left open, so that by screwing down the lamp sufficiently its contact point 19 may be caused to project beyond the lower edge of the socket portion 17 of the bracket, the base of the lamp constituting 75 the other place of contact as is the general practice. Thru the bracket 15, the socket is thus also in contact with one of the terminals, as terminal 12 of the cell 10.

In order to close the circuit to the lamp, 80 contact must, therefore, be established between the terminal 11 and the contact point 19 of the lamp; and this may be effected directly, as thru forcing downwardly the socket end of bracket 15 which is of a more 85 or less resilient nature. It is preferred, however, to establish the contact by means of the nut 13, adjustably mounted on the threaded terminal 11, as in turning said nut upwardly until its upper surface 90 contacts with the projecting contact point 19 of the lamp. Since the bracket 15 is made more or less resilient, an appreciable tension may be secured by screwing up the nut 13 sufficiently; and this will serve to 95 insure good contact between its said upper surface and the said contact point 19. When it is desired to break the connection, this may then be effected readily either by unscrewing the lamp 18 sufficiently or by screwing 100 downwardly the nut 13.

The construction of the bracket, moreover, admits of the convenient association therewith of a reflector member, as the member 20, which may be attached readily by 105 means of a spur 21 therefrom fitting thru a slot 22 properly placed in the bracket and near the socket 17. The cylindrical form of this socket may also be conveniently insured by means of a further spur 23 which 110 projects therefrom to extend thru a slot 24 of the wall of said bracket. The construc-

tion thus affords a simple, neat, inexpensive and efficient bracket member which may be readily secured to one of the terminals of the dry cell, while its other and free end is designed for receiving and retaining the lamp, the said bracket being so constructed, moreover, and positioned with respect to the other terminal of the dry cell, that contact may readily be established between it 10 and lowest contact place of the lamp, whose other place of contact makes electrical connection directly with the bracket itself and thereby with the first-named terminal.

I claim:—

- 15 1. An electric light fixture of the character set forth, comprising a bracket member consisting of a flat metal strip, substantially rigid and perforated at one end for attachment to one terminal of a dry cell, said strip 20 being inclined upwardly and brought into a vertical plane by a quarter twist, the other end of the strip being bent around to provide a socket for receiving a lamp, the socket being adjacent to the cooperating terminal of the dry cell, whereby contact may 25 be established between a lamp terminal and the corresponding cell terminal.
2. An electric light fixture of the character set forth, comprising a bracket member 30 consisting of a flat metal strip, substantially rigid and perforated at one end for attachment to one terminal of a dry cell, said strip

being inclined upwardly and brought into a vertical plane by a quarter twist, and the opposite end of the strip being threaded and 35 having a spur extending therefrom to fit thru a slot of the strip when bent around in a horizontal plane and providing thereby a cylindrical threaded socket for receiving a lamp, the socket being adjacent to the co-40 operating terminal of the dry cell, whereby contact may be established between a lamp terminal and the corresponding cell terminal.

3. An electric light fixture of the character set forth, comprising a bracket member 45 consisting of a flat metal strip, substantially rigid and perforated at one end for attachment to one terminal of a dry cell, said strip being inclined upwardly and brought into 50 a vertical plane by a quarter twist, the other end of the strip being bent around to provide a socket for receiving a lamp, the socket being adjacent to the cooperating terminal of the dry cell, whereby contact may 55 be established between a lamp terminal and the corresponding cell terminal, and a reflector mounted upon the vertically disposed portion of the bracket behind said socket portion.

Signed at New York, in the county of New York and State of New York, this 29th day of May, A. D. 1924.

JOHN M. ABRAMS.
